CARTON BLANK

Earl J. Graser, Monroe, La., assignor to
Olinkraft, Inc., West Monroe, La.

Filed Feb. 14, 1974, Ser. No. 442,610

Term of patent 14 years

Int. Cl. D9—99

U.S. Cl. D9—245

FIG. 1

FIG. 2

FIG. 1 is a top plan view of a carton blank showing my new design, the bottom plan view being a mirror image thereof; and

FIG. 2 is a top plan view of a modified form of the carton blank, the bottom plan view being a mirror image thereof.

The blanks shown in FIG. 1 and FIG. 2 are formed of conventional thickness material and the dash lines represent fold lines.

I claim:

The ornamental design for a carton blank, substantially as shown and described.
